(57) **CLAIM**

The ornamental design for molded handle grips for a utility cart, as shown and described.

DESCRIPTION

FIG. 1 is a right side view of the molded handle grips for a utility cart showing my new design;

FIG. 2 is a left side view thereof;

FIG. 3 is a front view thereof;

FIG. 4 is a back view thereof;

FIG. 5 is a top back perspective view thereof; and,

FIG. 6 is a bottom back perspective view thereof.

The broken lines in FIGS. 1-6 show portions of the cart body that are not part of the claimed design.

1 Claim, 3 Drawing Sheets
